UNITED STATES PATENT OFFICE.

FRANK A. STICKNEY, SR., OF PHILADELPHIA, PENNSYLVANIA:

DESIGN FOR A BRUSH-BRIDLE RETAINER.

SPECIFICATION forming part of Design No. 30,727, dated May 9, 1899.

Application filed April 12, 1899. Serial No. 712,807. Term of patent 7 years.

To all whom it may concern:

Be it known that I, FRANK A. STICKNEY, Sr., a citizen of the United States, residing at the city of Philadelphia, in the county of Philadelphia and State of Pennsylvania, have invented and produced a new and original Design for a Brush-Bridle Retainer, of which the following is a specification, reference being had to the accompanying drawings, forming part thereof, in which—

Figure 1 is a top or plan view of a bridle fastening or retaining device for paint-brushes or the like of the design of my invention, and Fig. 2 is a sectional view through the device on the line $x-x$ of Fig. 1.

The leading feature of my design consists of the shape, configuration, or outline of the brush-bridle retainer hereinafter described and claimed.

Referring to the drawings, a is the body of the device, which is circular in outline, with a central aperture a' and with wings b and b' ; of tapering form from the body to the ends; bluntly pointed, as illustrated in Fig. 1 of the drawings.

Having thus described my invention, what I claim as new, and desire to secure by Letters Patent, is—

The design for a brush-bridle retainer, substantially as herein described and shown.

In testimony whereof I have hereunto set my signature in the presence of two subscribing witnesses.

FRANK A. STICKNEY, SR.

Witnesses:

J. WALTER DOUGLASS,
THOMAS M. SMITH.
